UNITED STATES PATENT OFFICE.

DAVID ROBERTS AND KENNETH ROBERTS, OF GRANTHAM, LINCOLN, ENGLAND.

GOLF AND LIKE CLUB.

1,135,621.

Specification of Letters Patent. Patented Apr. 13, 1915.

Application filed May 7, 1914. Serial No. 836,990.

To all whom it may concern:

Be it known that we, DAVID ROBERTS and KENNETH ROBERTS, both subjects of the King of Great Britain, residing at Spittlegate Iron Works, Grantham, Lincoln, England, have invented new and useful Improvements in Golf and like Clubs, of which the following is a specification.

Our invention relates to improvements in golf-clubs and the like of the kind having interchangeable heads or striking faces, and has for its object to reduce the number of clubs or parts which must be carried while playing.

15 To this end our invention consists in providing a series of interchangeable heads so made and arranged that they can be attached to the stick or shaft in either of two positions so that each head is the equivalent 20 of two clubs.

In a suitable arrangement for carrying out the invention we provide the usual socket to which the stick or shaft is secured with an extension or head, preferably of a dovetail section, and disposed at a suitable angle relatively to the said socket or stick, which angle, in the case of a golf-club, may be the average angle of the striking faces of the several forms of club required, such for example, as 25 the niblick, cleek, mashie, driving iron, lofting iron, and putter. This dovetail or like socket extension is designed to receive the interchangeable heads, each of which for this purpose is provided at the back with a 30 number of lugs which together form the equivalent of a groove, of a dovetail or like shape, corresponding to that of the socket extension which is designed to fit into the same when the head is being attached to the 35 stick. In practice, we advantageously provide three dovetail lugs on each interchangeable head, two of which lugs constitute one side of the dovetail groove to be formed and are located near the outer edge of the head 40 45 with a space between them, while the third lug is designed to form the other side of the dovetail and is located at the center of the head, or in other words, between the first mentioned two lugs. By this arrangement 50 ready access can be had to the groove to remove any dirt or the like which may enter therein.

Any suitable means may be provided for securing the interchangeable heads in place 55 upon the dovetail or like socket extension.

For example, the said extension may be split longitudinally, preferably approximately at right angles to the face thereof on which the head rests, and means may be provided whereby the said split extension may be expanded or opened out after the head is placed in position. Suitable means for this purpose comprise a lug which is formed at the rear of the outer end of the extension and is formed with a screw hole with which 60 engages a screw, the end of which is tapered and enters a taper hole provided in the split end of the extension. By turning this screw the split ends are opened out, thus securely locking the loose head in place. The point 65 of the screw may be arranged to enter a hole formed in the loose head in order to prevent the latter from being dragged off the socket extension by rough usage. In some cases, the split extension may be formed with a 70 slightly raised or stepped surface on the dovetail faces near their outer ends as an additional lock or means of security.

The driving face of each of the loose 75 heads is formed at an angle with the back face which is adjacent to the split head, that is to say, the front or driving face is not parallel with its back face, so that by arranging the heads in the reverse way, a change 80 of the angle of the driving face relatively to 85 the shaft or stick is obtained; by this means each loose head is the equivalent of two ordinary clubs.

To enable the invention to be fully understood, we will describe it by reference to the 90 accompanying drawing, in which:—

Figure 1 is a front elevation of a golf-club having a detachable and reversible head constructed according to the invention. Fig. 2 is a side view thereof, and Fig. 3 is a rear view of the club. Figs. 4 and 5 are a side view and a rear view respectively of the form of head shown on the club in Figs. 1, 2 and 3, this head being of the iron or lofting iron type. Fig. 6 is a sectional plan view of the socket to which the shaft is attached. Fig. 7 is a sectional plan view of part of the socket shown in Fig. 6 and hereinafter more particularly described. Figs. 8 and 9 are views similar to Figs. 4 and 5 respectively of a cleek or a niblick head. Figs. 10 and 11 are also views similar to Figs. 4 and 5 respectively of a driving iron head, and a mashie head.

a represents the stick or shaft of the golf- 110

club and *b* the usual socket to which the said shaft or stick *a* is secured in the ordinary way.

c is the extension which is provided upon the socket *b*, this extension being, as shown, of a dovetail shape and being arranged at an angle relatively to the socket *b* or stick *a*. As described above this angle, in the case of a golf-club with respect to which the invention is here being specifically described, is the average angle of the striking faces of the several forms of club required.

d is the club head. In the drawing several forms of head are shown and each is furnished on its rear face with a dovetail groove designed to receive the aforementioned extension *c* of the socket *b*. The groove is formed by means of the two lower lugs *e* separated by a space *f*, and the upper lug *g* which is situated between the two lugs *e*. As will be observed the front face *h* of each head is not parallel to the rear face *i* thereof, so that by reversing the said heads relative to the extension *c* of the socket *b* the equivalent of two clubs can be obtained.

j is the longitudinal slot which is formed in the socket extension *c* and *k* is the lug which is provided upon the outer end of the said extension *c*, the said lug having the screw-threaded hole *l* designed to receive the screw *m*, the end of which is tapered, as shown at *n*, which tapered portion traverses the taper hole *o* provided in the split end of the extension, and enters the hole *p* formed in the head *d*. Two of these holes *p* are provided, as shown, in order to allow of the reversal of the head with respect to the socket. With this construction it will be understood that to attach a head *d* to the shaft *a* it is merely necessary to pass the dovetail extension *c* of the socket *b* into the groove provided by the lugs *e* and *g* upon the head, and to then turn the screw *m* so as to force the taper end thereof into the split end or slot *j* of the socket extension *c*, thereby opening out the said split end and causing it to tightly grip the head.

To enable wear to be compensated for the screw-threaded hole *l* is made in a bush *P* which is itself screwed in a hole in the lug *k*. The bush *P* is made with a longitudinal slot *l* to receive a key, such as *q* Fig. 7 by means of which it can be turned to adjust its position in the hole in the lug *k*. The screw thread of the bush *P* is of different pitch or hand from that of the screw *m*.

As will be understood the invention is applicable to clubs made of any of the usual materials, such as iron or wood.

60 Claims:

1. In a golf or like club, the combination with a stick or shaft, of a detachable reversible head having a single driving face and means connecting said stick or shaft and said head in either of two relatively re-

versed positions, whereby the single face will be presented at different angles relative to the stick.

2. In a golf or like club, the combination with a stick or shaft, of a detachable reversible head having a single driving face, means connecting said stick or shaft and said head, whereby the single face will be presented at different angles when said head is placed upon said stick in either of two relatively reversed positions, and means for locking said connecting means.

3. In a golf or like club, the combination with a stick or shaft, of a detachable reversible head having a single driving face, means connecting said stick or shaft and said head, whereby the single face will be presented at different angles when said head is placed upon said stick in either of two relatively reversed positions, means for locking said connecting means, and means for compensating for wear in said locking means.

4. In a golf or like club, the combination with a stick or shaft, of a detachable reversible head having a groove at its rear, the driving face of said head being formed at an angle to the rear face for the purpose of presenting the driving face at different angles for driving, an extension on the stick or shaft which engages the groove in said head in either of two reversed positions of the latter, and means for locking the said extension in the groove.

5. A golf or like club, comprising two members consisting of a stick, and a detachable reversible head having a single driving face formed at an angle to its rear face, one of said members being provided with a groove and the other of said members being provided with a dovetail extension, and means connecting said grooved member and said dovetail member, whereby the single face of the head will be presented at different angles when said head is placed upon said stick in either of two relatively reversed positions.

6. In a golf or like club, the combination with a stick or shaft, of a detachable reversible head, the driving face of which is formed at an angle with the rear face for the purpose of presenting the driving face at different angles for driving, and means for securing the head to the stick in either of two relatively reversed positions.

7. In a golf or like club, the combination with a stick or shaft provided with a dovetail extension, a detachable reversible head, the driving face of which is formed at an angle to the rear face for the purpose of presenting the driving face at different angles for driving, a dovetail groove in the rear face of said head, which groove receives the dovetail extension of the stick in either of two reversed positions of the head respec-

tively to the stick extension, and means for locking said extension in said groove.

8. In a golf or like club, the combination with a stick or shaft provided with a dovetail extension, a detachable reversible head, the driving face of which is formed at an angle to the rear face for the purpose of presenting the driving face at different angles for driving, a dovetail groove in the rear face of said head, which groove receives the dovetail extension of the stick in either of two reversed positions of the head respectively to the stick extension, and means comprising a split end on the extension in combination with an expanding screw, for locking the said extension in the groove.

9. In a golf or like club, the combination with a stick or shaft provided with a dovetail split extension, a detachable reversible head, the driving face of which is formed at an angle with the rear face for the purpose of presenting the driving face at different angles for driving, a plurality of lugs on the rear face of the head to receive the dovetail extension of the stick in either of two reversed positions of the head relatively to the stick extension, an aperture provided in said extension and a taper screw engaging said aperture and said split extension for expanding said extension to lock the extension in said groove.

10. In a golf or like club, the combination with a stick or shaft having a split extension, a detachable reversible head formed

with a groove to receive the split extension, in either of two reversed positions, the driving face of said head being formed at an angle to its rear face for the purpose of presenting the driving face at different angles, a lug upon the extension, an adjustable bush provided in said lug and having a screw threaded aperture, and a taper screw passing through said bush and through the split in said extension.

11. In a golf or like club, the combination with a stick or shaft having a split extension, a detachable reversible head having a groove on its rear side to receive said extension in either of two reversed positions of said head relative to said extension, said head having a driving face which is formed at an angle with the rear side of said head for the purpose of presenting the driving face at one angle when the head is placed on the extension in one direction and at a different angle when placed on the extension in the opposite direction, a lug upon the extension and having an aperture provided therein, a taper screw passing through said aperture and through the split in said extension, and a plurality of holes provided in said head into which the screw enters when the head is placed in its different positions.
